Atty

United States Patent Office.

HENRY L. HANSON, OF PORTLAND, MAINE.

Letters Patent No. 69,091, dated September 24, 1867.

IMPROVEMENT IN LAMPS.

The Schedule referred to in these Letters Patent and making part of the same.

TO ALL WHOM IT MAY CONCERN:

Be it known that I, HENRY L. HANSON, of Portland, in the county of Cumberland, and State of Maine, have invented a new and useful Improvement in Lamps; and I hereby declare the following to be a full, clear, and exact description thereof, which will enable others to make and use the same, reference being had to the accompanying drawings, forming part of this specification, in which—

Figure 1 represents a side elevation of a lamp top with my improvement attached thereto.

Figure 2 is a view of the top of the glass cylinder in a lamp top illustrating the method of attaching my improvement.

Figure 3 is a section of the top part of the same.

Figure 4 shows the metallic detachable cone.

Same letters show like parts.

The superior excellence of glass cones is well known, but they are still liable to a single disadvantage, which it is the purpose of my invention to correct, viz, the edges of the slot or slit in the top of the cone through which the flame protrudes when the lamp is burning is by the operation of the heat continually chipping, cracking, and breaking, so that in time the cone will become virtually useless by such continued breaking. There is a kind of these glass cones which are set upon and are a part of a glass cylinder, and they are used in a lamp top similar to that represented in fig. 1. My improvement has its intended application to such cylinder, or to a similar one, and it dispenses with the glass cone and its consequent inconvenience.

Upon the top of the cylinder I first construct a shoulder, *a*, around the edge of the circular opening in the top of said cylinder. I also make two recesses, *b*, in the edges of the opening, through the entire thickness of the glass of which the cylinder is formed. Upon this shoulder *a* rests the lower end of the detachable metallic cone, which is the subject of my invention, and into the recesses *b* fit two ears, which project from the lower edge of said cone. *c* shows the cone, and *d* the ears. In fig. 1 the cone is shown in position, the glass cylinder being represented by *A*. The shoulder *a* and recesses *b*, together with the ears *d*, sufficiently confine the cone, allowing at the same time the necessary space for its expansion and contraction, in order that not being closely bound by the glass cylinder *A* there will be no liability of its cracking the same.

I do not, of course, claim the glass cylinder or the metallic cone except when constructed and combined as heretofore described, with a view to preserve as large a proportion of illumination from the lamp as possible, using at the same time the removable metallic cone to prevent the breaking and chipping, as before described. I do not claim a cylinder of mica with a metallic rim at the top and bottom, the top rim having secured to it a diaphragm constructed of a transparent material or a highly polished metal, such as is seen in the Patent of Joseph Ridge, April 15, 1862; neither do I claim the combination of this diaphragm with a cylinder of mica having a perforated metallic bottom, and with a short chimney, as claimed in the third claim of said patent. In my invention I apply a removable metallic cone, having two ears, to a glass cylinder such as exhibited in the drawing, said cylinder having a shoulder around the inner edge of the perforation or opening in its top, and having also two slots cut into the edges of said opening to receive the ears on the cone. Should the cylinder become broken, the cone could be applied to another.

What I claim as my invention, and desire to secure by Letters Patent, is—

The arrangement of the removable metallic cone on the glass cylinder, in the manner and for the purposes set forth.

Witnesses:

WILLIAM H. CLIFFORD,
WM. FRANK SEAVEY.
